FOLDABLE CRIBBAGE BOARD

George H. Miller, Athol, Mass.

Application February 17, 1944, Serial No. 522,834

1 Claim. (Cl. 235—90)

The present invention relates to new and useful improvements in tally boards or scoring devices of a type in which pegs are inserted into holes in the board for scoring points in the playing of games, such as for example in the game of Cribbage.

An important object of the present invention is to provide a Cribbage board composed of foldable sections to produce a compact device which may be easily carried in a person's pocket, when not in use.

A further important object of the invention is to improve the appearance of the device by enclosing the rigid sections which compose the board in leather or other flexible covering and to provide the sections of the covering, adjacent their free ends, with fastening devices and by means of which the device may be maintained in its folded position.

A still further object of the invention is to provide a plurality of pockets in the region of the fold line of the sections of the game board and in which the pegs used for indicating the score may be conveniently carried.

An additional object is to provide an article of this character of simple and practical construction, which is neat and attractive in appearance, relatively inexpensive to manufacture and otherwise well adapted for the purposes for which the same is intended.

Other objects and advantages reside in the details of construction as more fully hereinafter described and claimed, reference being had to the accompanying drawing forming part hereof, wherein like numerals refer to like parts throughout and in which:

Figure 1 is a plan view showing the game board in open position.

Figure 2 is a side elevational view thereof.

Figure 3 is a fragmentary sectional view taken substantially on the line 3—3 of Figure 1.

Referring now to the drawing in detail, wherein for the purpose of illustration I have disclosed a preferred embodiment of the invention, the numerals 5 and 6 designate a pair of elongated relatively thin boards constructed of wood or other suitable material, the boards being of duplicate construction and of substantially rectangular form with one end of each board rounded, as shown to advantage in Figure 1 of the drawing.

The boards 5 and 6 are secured in position between inner and outer covers 7 and 8, the covers preferably being constructed of leather or other suitable flexible material and the covers are of an area in excess of the combined areas of the

boards 5 and 6 so that the adjacent ends of the boards are spaced apart and so as to provide marginal edges 9 for the covers extending around the outer sides and ends of the boards.

5 The margins, at the sides and outer ends of the boards are provided with stitching 10 to secure the inner and outer covers together.

The inner and outer covers 7 and 8 are also connected adjacent the inner ends of the boards 5 and 6 by single rows of stitching 11 and 12, respectively, extending transversely of the covers and between the rows of stitching 11 and 12 is a transverse row of stitching 13 also connecting the inner and outer covers to provide a plurality of pockets 14 which are open at each side edge of the board.

The pockets at each side of the board are separated by a row of stitching 15 which extends in a directional longitudinally with respect to the 20 board whereby to provide individual pockets at each side edge of the board and into which pegs (not shown) may be removably inserted.

Each of the boards 5 and 6 is provided with a plurality of openings 16 arranged in rows in accordance with the conventional form of Cribbage Board and the inner cover 7 is also provided with openings 17 which register with the openings 16 so that the pegs used in keeping the score may be inserted through the openings 17 of the cover into the openings 16 of the board in a manner as will be apparent.

Since the covers 7 and 8 are of flexible material the same may be folded along the transverse line 13 with the inner cover 7 innermost and the inner cover is provided adjacent its end edges with male and female snap fasteners 18 and 19 adapted for engagement with each other to secure the board in its folded position.

From the foregoing it will be apparent that the 40 Cribbage board may be used in its usual manner when the same is in its open position and when not in use the board may be folded into a compact form for conveniently carrying the same.

It is believed the details of construction and 45 manner of use and advantages of the device will be readily understood from the foregoing without further detailed explanation.

Having thus described the invention, what I claim is:

50 A game score board comprising a plurality of elongated rigid board sections, said sections being arranged in spaced apart end to end relation, flexible strips of material covering the opposite sides of the sections, said sections and one of said cover strips having registering openings, the mar-

ginal edges of the cover material extending beyond the edges of the board sections, stitching connecting the marginal edges of the cover material, spaced parallel transverse rows of stitching connecting the cover material in the region of the spaced apart ends of the board sections and defining elongated pockets in the cover material which are open at each side edge of the material,

5 a row of stitching closing the inner ends of the pockets, said cover material being foldable along one of said transverse rows of stitching to position the board sections one upon the other, and separable fastening devices carried by the cover material for securing the same in folded position.

GEORGE H. MILLER.
